UNITED STATES PATENT OFFICE.

HENRY H. TAYLOR AND MYRON B. HAMMOND, OF BRIDGEPORT, CONNECTICUT,
ASSIGNORS TO THE THOMAS P. TAYLOR COMPANY, OF BRIDGEPORT, CONNECTICUT, A CORPORATION OF CONNECTICUT.

GARTER.

Application filed November 6, 1922. Serial No. 599,255.

To all whom it may concern:

Be it known that we, HENRY H. TAYLOR and MYRON B. HAMMOND, both citizens of the United States, residing at the city of 5 Bridgeport, county of Fairfield, and State of Connecticut, have invented certain new and useful Improvements in Garters; and we do declare the following to be a full, clear, and exact description of the invention, 10 such as will enable others skilled in the art to which it appertains to make and use the same.

This invention relates to certain new and useful improvements in garter clasps, and 15 pertains more especially to men's garters.

The primary object of the invention is to provide a clasp in which a two-point connection is formed between the male and female members of the clasp so as to maintain the 20 relatively wide as well as the non-elastic pad flat and snug about the leg of the wearer, to thereby increase the holding efficiency of the garter.

A further object of the invention is to provide 25 means for securing the male member to the webbing of the garter in a firm and effective manner and in such way as to prevent movement of the male member out of its normally flat relation to the webbing or 30 garter.

The invention still further aims to provide a garter clasp construction which is not only possessed of the foregoing novel features, but which also can be economically and 35 easily manufactured.

The invention has still further and other objects which will be later set forth and manifested in the course of the following description.

40 In the drawings:—

Figure 1, is a plan view of the invention applied to a garter, the latter shown in fragment.

Figure 2, is a section on line 2—2 of 45 Figure 1;

Figure 3, is a detail perspective view of the male member in detached position, and

Figure 4, is a similar view of the female member.

50 In proceeding in accordance with the present invention, the female member 1 embodies a clasp bar 2 that extends across the end A of the leg encircling webbing and is

secured by means of a rear bar 3 having a heel extension 4 between the folds of the 55 webbing as shown in Figure 2. The heel extension 4 is secured by a clip or fastening 5 within the webbing and affords a finger grip which maintains the bar 2 against pivotal movement and also acts to stiffen the end A 60 of the webbing, enabling the user to more easily and quickly manipulate the garter in use thereof.

The present invention more particularly relates to the male member of the clasp, and 65 embodies a sheet metal plate 6 which is formed with hooks 7, that may be lanced or struck-out therefrom as depicted in Figure 3 of the drawings. These hooks engage the bar 2 and are disposed to lie adjacent to the 70 respective side edges of the garter. The plate 6 is preferably formed with an opening 8 through which a piece of tape 9 is threaded, the ends of the tape extending outwardly beyond the inner side of the plate. 75

A flexible tab 10 is folded about the metal plate 6 and the hooks 7 are projected therethrough, the ends 11, 11, of the tab embracing the ends 9 of the tape, the latter being spread or given a divergent relation as illustrated in Figures 1 and 3 of the drawings. The pad P is non-elastic, being preferably 80 made of leather, and has its edge parts B separated to receive the ends 11, 11, of the tab 10. Stitching 12 is then applied to the parts to simultaneously secure the tape, and the tab 10, with the male member 6 in the latter, to the pad. Since the hooks 7 extend through the tab 10, it will be apparent that 85 the plate 6 is held against movement relative to the tab.

The function of the tape 9 is to prevent 90 accidental tilting of the plate when the hooks or studs 7 are placed under tension when engaged with bar 2 in use of the garter, which tilting would prove uncomfortable and annoying to the wearer, but this tape is precautionary rather than necessary and may be omitted.

With the present invention, it will be seen 100 that the two studs or hooks 7 engage the bar 2 at the end parts thereof which two point connection holds both the wide webbing and the pad P flat and snug against the leg of the wearer and also prevents pivoting of the 105 male and female members, such as frequently

occurs with fastenings in which but one central male and female member are employed.

What is claimed is:—

1. In a clasp for garters of the pad type, 5 a non-elastic pad, a leg encircling webbing one end of which is permanently secured to one side of said pad, a female member having a bar connected to and extending across the free end of the webbing, a metal plate 10 having an aperture, tape threaded through the aperture and having its ends extending beyond the inner side of the plate, a short flexible tab folded to have sides which embrace the metal plate and the tape ends 15 there-between, said plate having a spaced pair of studs struck out therefrom and extended through one side of the folded tab to engage the bar of the female member adjacent the ends of the latter, the pad receiving 20 the free ends of the folded tab between its sides, and stitching extending through the pad sides, through the sides of the tab and through the tape ends.
2. In a garter clasp, a non-elastic pad, a 25 leg encircling webbing one end of which is permanently secured to one side of said pad, a female member having a bar connected to the free end of the webbing, a plate having an aperture, tape threaded through the aperture and extended beyond the inner plate side, a flexible tab folded about the plate and tape, said plate having a plurality of spurs extended through one side of the tab and formed to engage the bar of the female 30 member, and stitching for securing the tab and the tape to the opposite end of the pad.
3. In a garter clasp, a non-elastic pad, a 35 leg encircling webbing one end of which is

permanently secured to one side of said pad, a female member on the free end of the webbing, a male member including a plate, a piece of fabric threaded through and extended beyond the plate, a flexible tab embracing the plate and the extended part of the threaded piece of fabric, stitching for securing the tab and fabric to the opposite edge of the pad, and a plurality of studs carried by the plate and extended through the tab to engage the female member. 40

4. In a garter clasp, a central non-elastic pad, leg encircling webbing secured at one end to one side of the pad, a female clasp member on the other end of the webbing, a male member including a plate, a flexible member folded about the plate, a 45 plurality of studs carried by the plate and extended through the flexible member to engage the female member, and stitching for securing the flexible member to the opposite end of the pad. 50

5. In a garter clasp, a central non-elastic pad, leg encircling webbing secured at one end to one side of the pad, a female member carried by the free end of the webbing, a male member carried by the opposite side of 55 said pad and including a metal plate having a plurality of studs to engage the female member, and means to secure the plate to the pad including a flexible member engaged about the plate and secured to the pad and 60 having said studs projected therethrough.

In testimony whereof we affix our signatures hereto:

HENRY H. TAYLOR.
MYRON B. HAMMOND.
